UNITED STATES PATENT OFFICE.

PAUL SIMON, OF CLASSON POINT PARK, NEW YORK.

AMUSEMENT-PARK DEVICE.

1,426,418.

Specification of Letters Patent. Patented Aug. 22, 1922.

Application filed August 13, 1921. Serial No. 491,957.

To all whom it may concern:

Be it known that I, PAUL SIMON, a citizen of the United States, residing at Classon Point Park, in the county of the Bronx 5 and State of New York, have invented certain new and useful Improvements in Amusement-Park Devices, of which the following is a specification.

The invention relates to amusement devices such as are used at parks and amusement places and the particular object of the 10 device is the provision of a form of carrousel or merry-go-round composed of a number of passenger carrying cars secured to bars attached to a prime mover situated in the center of the track.

Another object of the invention is the provision of a device having the said cars run on a track composed of ridges forming a 20 number of undulating curves giving the passengers the sensation of riding a boat in a stormy sea or of riding in a car over hill and dale.

These and other objects will become apparent in the description to follow in which characters of reference refer to the like-named parts in the drawing.

Referring briefly to the drawings, Figure 1 represents a section taken on the line 1—1 30 of Figure 3 and shows the curved riding surface of the track and cars riding thereon.

Figure 2 is a plan view of the connecting arm and shows the means provided for the 35 swiveling of the cars as they rotate about the axis of the track.

Figure 3 is a plan view of the entire device showing the motor and associated means for rotating the cars on the track.

Figure 4 is an elevational section of one 40 of the cars taken through one of the swiveling centers of the device showing the means for providing a side-movement of the car with respect to the track, purpose of the same will be more fully hereinafter described.

Referring more in detail to the drawings the numeral 10 is used to designate a concrete bed having the upright joists 11 securely imbedded therein for a suitable 50 distance so that the beams 12 carrying a platform 13 are relatively free from side strain which would tend to collapse the understructure.

The track 15 is annular in outline and is 55 composed of a number of plates of steel or other suitable material bent to form a series

of undulating curves, the same gradually generating into a rise and then gradually receding into a dip-form whence the curve repeats itself. It is to be understood that 60 the number of dips can be increased by enlarging the diameter of the track or vice versa.

A large casting centrally located with respect to the track, is imbedded in the concrete to a depth which will insure rigidity to the various rotating members and consists of a base 14 having a wall 15 encircling the same. Integral with the wall and extending upwardly at an angle so as to form 70 a bearing hub 17 are the supporting frame members 18. A lug extension 19 extending upwardly from base 14 and having a hole therein is adapted to receive the lower end of the shaft 20. Fixed to the said shaft at 75 its lower end is a relatively large worm gear 21 adapted to mesh with a worm 22 which is secured to the rotor of the electric motor 23.

Secured to the upper end of the shaft 20 80 is a hexagonal sided wheel 24 having an inner and outer hub with the spokes 24 connecting the two. The surfaces on said wheel have the ears 25 extending therefrom having holes therein and spaced somewhat apart so 85 as to receive the extensible bars 26 therebetween, the latter being pivotally secured to the ears by the pins 27 at the larger end. The bar members 26' are secured to ears 25' by similar pins. Ears 25' are an extension 90 of brackets 28 which are secured to passenger cars 29 having the seats 30 built therein. The cars are preferably of a capacity which will comfortably seat twenty-four persons.

As the wheel 24 is rotated by the power 95 unit it will be seen that the cars will follow the path of the track but in passing over the successive rises and dips, the bars attached to the cars will be elongated and the cars will further describe a small arc. For this 100 reason the bar members 26 and 26' are constructed as follows:—The long heavy bar 26 has a recess therein having the plate member 32 rigidly secured thereto. Passing through a hole in the said plate is a shaft or 105 plunger rod 31 having a collar 35 fixed to the end thereof. An expansion spring 34 is wound on the said plunger rod between plate 32 and collar 35. It will be seen that the bar member 26' is normally urged in the 110 direction of bar member 26. It is apparent from Figure 1 that the car in passing from

the top of the rise to the bottom of the dip, the plane in which the car is riding and the length of the bar members is constantly changing and a device of the type described therefore necessary. As the car reaches the lowest part of the dip of the track the action reverses itself and the bar members come gradually back to their normal length.

Due to the law of centrifugal force and 10 the constant change of surface direction there is a tendency to capsize the cars and a means is provided to permit a certain amount of side slip which will counteract the tendency to capsize. Wheels 36 are provided 15 with oppositely disposed rounded shoulders 36 which are adapted to always keep the wheels on contact with the track and prevent side slip of the same. Centrally located on the axle 37 and securely fixed thereto is the 20 collar 38 which has expansion springs 39 oppositely disposed to each other and of equal tension and are further kept in contact with the collar by the walls of the casting 40. In passing over the dips centrifugal 25 force will tend to force the car outwardly from the center thereby compressing one of the springs 39 which due to its resiliency

will restore the car to its normal position relative to the centre of the axle with no attendant jar. The member 40 has a swivel 30 extension 41 mounted in a hole of member 42 which is secured to the under-side of the floor of the car, which permit the wheel trucks to follow the track outline.

I claim:

A device of the class described comprising a power unit, an upright shaft actuated by said power unit, a hexagonal sided wheel secured to the upper end of said shaft, each side adapted to have one end of extensible 40 bar members pivotally secured thereto, passenger cars pivotally secured to the opposite ends of the said bar members and adapted to tractionally ride on the surface of an annular track a collar fixed to the axle of the 45 traction trucks, oppositely disposed springs mounted in a housing, said housing having a pivoting member adapted to swivel in a member fixed to the floor of the passenger car and a means for allowing side slip of the 50 passenger car substantially as shown.

In witness whereof I affix my signature.

PAUL SIMON.
